DETACHABLE HANDLE SCREW DRIVER

Raymond Garbs, Kankakee, Ill.

Application July 1, 1949, Serial No. 3,657

Term of patent 14 years

(Cl. D93—4)

To all whom it may concern:

Be it known that I, Raymond Garbs, a citizen of the United States, residing at Kankakee, State of Illinois, have invented a new, original, and ornamental Design for a Detachable Handle Screw Driver, of which the following is a specification, reference being had to the accompanying drawing, forming a part hereof.

Figure 1 is a side elevational view of a detachable handle screw driver, showing my new design;

Figure 2 is an end elevational view;

Figure 3 is an elevational view showing the handle in an alternate position; and

Figure 4 is a sectional view taken along line 4—4 of Figure 1.

I claim:

The ornamental design for a detachable handle screw driver, as shown.

RAYMOND GARBS.
